DESIGN FOR A REFRIGERATOR CABINET

Ralph E. Kruck, Springfield, Mass., assignor to
Westinghouse Electric & Manufacturing Com-
pany, a corporation of Pennsylvania

Application October 14, 1938, Serial No. 80,442

Term of patent 7 years

To all whom it may concern:

Be it known that I, Ralph E. Kruck, a citizen
of the United States, residing at Springfield, in
the county of Hampden and State of Massachu-
setts, have invented a new, original, and orna-
mental Design for a Refrigerator Cabinet, of
which the following is a specification, reference
being had to the accompanying drawing, form-
ing a part thereof.

The single figure is a perspective view of the
refrigerator cabinet showing my new design.

I claim:

The ornamental design for a refrigerator cab-
inet, substantially as shown.

RALPH E. KRUCK.
